UNITED STATES PATENT OFFICE

ERICK SJOSTRAND AND LAWRENCE J. SEYMOUR, OF WASECA, MINNESOTA

SPRING MATTRESS

Application filed May 1, 1930. Serial No. 449,034.

This invention relates to spring mattresses and particularly to a spring mattress which includes a frame adapted to be mounted on or supported by the bed frame itself.

3 The present invention designs to provide a spring mattress which entirely does away with the use of coiled bed springs, particularly the vertical bed springs wherein double coils are used, one inside of the other, 10 which are unsanitary and prevent proper cleaning from lint and dust.

15 A further object is to provide a spring mattress which has all the resiliency of the present coil spring construction and at the same time eliminates the use of these coiled springs.

20 A further object is to provide a spring mattress which includes double acting brackets on each corner of the mattress which suspends the mattress fabric and which is 25 resiliently connected to an under frame, which in turn is supported upon the bed frame proper.

25 A further object is to provide means whereby all side sway of the mattress is prevented without restricting its resiliency.

30 A further object is to provide means whereby the upper fabric of the spring mattress may be tensioned from time to time.

35 Other objects will appear in the course of the following description.

Our invention is illustrated in the accompanying drawings, wherein:—

Figure 1 is a side elevation of a spring 40 mattress constructed in accordance with our invention;

Figure 2 is an end elevation of the same;

Figure 3 is a fragmentary detailed plan 45 view of one corner of the under frame of the mattress;

Figure 4 is a vertical sectional view of one of the supporting brackets and a portion of the connecting rod;

Figure 5 is an under side elevation of the 50 bracket shown in Figure 4.

Our improved mattress includes in its construction, the end angle irons 10. These end angle irons are designed to be connected to the fabric 11, which is preferably of wire, 55 by means of springs 12 having hooks at their

ends engaging respectively in the end angle iron 10 and in the fabric. Attached to each angle iron 10 by the pins 14 are the brackets 15, these brackets as illustrated in Figure 5 being each formed with a middle circular 55 socket 16 and two legs 17 and 18.

The legs are open on their inside faces and the legs are cut away at 19 so as to reduce the weight of metal as much as possible. The leg 18, it will be seen, is angularly disposed with reference to the leg 17 of the bracket.

The leg 17 at its upper end is connected by pins 14 as previously described to the angle iron 10. There are preferably two of these brackets for each angle iron 10, the brackets being located adjacent the ends of the iron 10. There are two of these brackets, therefore, at each end of the mattress and these brackets are connected by two longitudinally extending tubular rails 20 formed of metal pipe, the 70 rails being inserted within the sockets 16 and being screw-threaded at their ends for engagement with the lock nuts 21 which bear against the ends of the sockets 16. By turning these lock nuts in one direction or the other, it is possible to force the brackets away from each other or permit the brackets to move inward toward each other.

Disposed on a level below the tubular rails 20 is an under frame, rectangular in plan view 80 and formed of angle irons, the angle irons being designated 22. This frame is less in area than the area of the frame defined by the end angle irons and the fabric and the corners of the under frame are braced by 85 the corner braces 23 riveted to the angle irons.

The lower ends of the brackets are formed to provide inwardly projecting flanges or webs 24 and are perforated for engagement by the hooked ends of a plurality of coiled contractile springs 25 shown as three in number, the opposite ends of the springs being hooked and engaged with perforations 26 in the end angle irons 22 of the under frame. 90 These angle irons 22 are provided with angular hangers 27 which are adapted to engage over the angle iron bed rails of a metal bed frame.

If a mattress is intended to be supported 100

upon a bed frame of wood having slats 29, then this under frame rests upon these slats.

It will be seen that with this construction the under frame supports the mattress by engagement with the bed frame, that the brackets are supported from the under frame by the highly tempered tension springs 25 and that the end angle irons and the brackets cannot move inward toward each other because they are held apart by the tubular side rails 20. Thus the mattress is suspended by the springs 25. Inasmuch as there are three of these springs at each corner, the mattress is held from any swaying movement as any lateral movement will be resisted by the angularly disposed springs 25 while all three of the springs 25 will yieldingly resist the downward movement of the mattress. The fabric 11 is supported at intervals by the springs 12. By turning up on the nuts 21, the brackets and, of course, the end angle irons 10 may be forced away from the brackets and angle iron at the opposite end of the bed and thus the mattress may be tensioned to any desired amount.

The desirability of this mattress lies wholly in the suspension of the top element of the mattress (the fabric 11 and the springs 12) from the under frame, this construction giving the same resiliency as the present coiled springs give but eliminating a great number of coils and noise-making wearing parts. This mattress can be used equally as well on a wooden bed as on an iron bed. The brackets are preferably made of cast aluminum alloy in order to secure lightness of the spring over cast iron brackets.

Obviously the tubular side rails 20 may have threaded engagement with the socket 16 and thus by rotating the tubular rails 20, the brackets may be forced further apart from each other or allowed to come toward each other, but we prefer the construction illustrated in Figure 4 where the socket 16 is unscrew-threaded as regards its interior face. We do not wish to be limited, however, to the use of a screw-threaded rail 20, though this provides for adjustment from time to time. It is necessary that the lower leg 18 of the bracket 15 be angularly disposed with relation to the upper portion in order to prevent the lower end bracket coming in contact with any portion of the bed as may possibly happen with a "bow" end bed or a straight wooden bed. Obviously, however, we do not wish to be limited to this particular form of bracket.

We claim:—

1. A spring mattress including a plurality of normally upright supporting brackets at each end of the mattress, upper end members connected to the upper ends of the brackets, a fabric web resiliently engaged at intervals with the upper end members, a rigid under frame adapted to rest upon a bed frame,

70 springs yieldingly connecting the lower ends of the brackets to the under frame, and longitudinally extending rails disposed in a plane between the under frame and the fabric web extending between the brackets at opposite ends of the mattress and holding said brackets from inward movement, each bracket having a socket intermediate its ends and loosely receiving the extremity of the rail, each extremity of the rail being screw-threaded and nuts engaging the screw-threads and bearing against the corresponding brackets whereby the brackets may be forced further from each other or permitted to move toward each other to thus tension both the upper and lower springs.

75 2. A mattress of the character described, comprising end angle irons, a plurality of brackets attached to each angle iron and extending downward therefrom, each bracket being formed with a medially disposed socket, longitudinally extending rails loosely engaged in the sockets of opposite brackets, and screw-threaded nuts engaging said threads and bearing against the brackets, a rigid rectangular under frame less in length than the distance between the end angle irons and brackets and having means whereby it may be engaged with the bed frame and supported thereon, coiled contractile springs connecting said under frame to the lower ends of said brackets, a fabric web, and coiled contractile springs connecting said fabric web with the first named angle irons.

80 3. A mattress of the character described, comprising end angle irons, a plurality of brackets attached to each angle iron and extending downward therefrom, each bracket being formed with a medially disposed socket, longitudinally extending rails loosely engaged in the sockets of opposite brackets, and screw-threaded nuts engaging said threads and bearing against the brackets, a rigid rectangular under frame less in length than the distance between the end angle irons and brackets and having means whereby it may be engaged with the bed frame and supported thereon, a plurality of horizontally disposed coiled contractile springs connecting the lower end of each bracket to the adjacent end of the under frame, certain of the springs being disposed in divergent relation to each other to thereby counter-act lateral sway, a fabric web, and coiled contractile springs connecting said fabric web with the first named angle irons.

85 In testimony whereof we hereunto affix our signatures.

ERICK SJOSTRAND.

LAWRENCE J. SEYMOUR.
